UNITED STATES PATENT OFFICE.

JOSEPH MOSHER, OF TAFT, CALIFORNIA.

BEER-COOLER.

1,104,997.

Specification of Letters Patent. Patented July 28, 1914.

Application filed April 26, 1913. Serial No. 763,857.

To all whom it may concern:

Be it known that I, JOSEPH MOSHER, a citizen of the United States, residing at Taft, in the county of Kern and State of California, have invented certain new and useful Improvements in Beer-Coolers, of which the following is a specification, reference being had to the accompanying drawings.

10 This invention relates to new and useful improvements in cooling devices and more particularly to cooling devices for beer kegs and the like and the primary object of the invention resides in providing a cooling device which is adapted for application to an improved keg which will be entirely sanitary in every respect.

15 A further object of the invention resides in providing a beer container designed to receive an ice container therein and resides in providing a wire mesh basket for reception in the ice container.

20 Still another object of the invention resides in providing a device which is simple and durable in construction, inexpensive to manufacture and one which will be very efficient and useful in operation.

25 With these and other objects in view, the invention consists in the novel features of construction, combination and arrangement of parts as will be hereinafter referred to and more particularly pointed out in the specification and claim.

30 In the accompanying drawings forming a part of this application Figure 1 is a side elevation of the device completely set up in use. Fig. 2 is a vertical section therethrough; Fig. 3 is a plan view of the device.

35 In describing my invention, I shall refer 40 to the drawings in which similar reference characters designate corresponding parts throughout the several views and in which—

45 1 indicates a liquid container designed in the shape of a barrel and formed preferably of glass, the outer face thereof, at the upper and lower ends being provided with pairs of ribs 2, between which are disposed the metal hoops 3. The bottom of this container 1 is formed integral with the side walls 50 thereof and is provided with the inlet and outlet tubes 4 and 4' respectively and the upper or open end of the container is provided with an enlarged threaded opening 5, the purpose of which will be hereinafter and 55 more particularly set forth. An opening is formed in the wall of the container 1, adja-

cent the bottom thereof, in which is mounted a faucet 6, whereby the contents of said container may be extracted, when desired. An additional glass container 7 is also provided, the same being of smaller dimensions than the container 1, and having the wall thereof at the upper end threaded, as shown at 8, whereby to be engaged with the threaded opening 5 of the container 1. The upper end of the container 7 is provided with an annular flange 9 which, when said container 7 is properly disposed in the container 1, rests upon the upper peripheral edge of said container 1. I have also provided a cylindrical basket 10 formed of wire mesh to be introduced in the container 7, said basket having the top thereof provided with a closure. Ice is adapted to be disposed in the basket 10 and the latter inserted in the container 7, after the same has been placed in the container 1, so that the liquid contents of said container 1 may be cooled and at the same time kept free from dirt, and other extraneous matter in the ice. I have also 75 provided a closure 11 for the device which is adapted to be seated on the upper peripheral edge of the container 7, when the latter is disposed in the container 1, a knob or handle member 12 being provided thereon 80 for the ready operation of the same. An air inlet pipe 13 is mounted in the upper peripheral edge of the container 1, for obvious purposes and a pet-cock 14 is formed in said tube to permit the air to be entered or entirely cut-off, as desired. As the ice melts 85 in the basket 10, the same will be retained in the container 7 and I have provided a means for the extraction thereof from said container, without the removal of the container 7 from the container 1. To this end, 90 a siphon is provided consisting of a tubular member 15 bent in substantial U-shaped form, and the one end thereof is adapted to be received in the container 7, while the opposite end, projecting outside of the container 1, has connection through the medium of a T-joint 16 with a water pressure supply 17. The free end of the last 95 mentioned arm of the siphon leads to a sewer or other waste connection 18, and it is obvious from this construction that when the water from the supply is permitted to pass to the sewer connection, a suction is formed thereby and the water within the 100 container 7, is drawn outwardly.

105 As shown in Fig. 1, a battery of kegs or

barrels 19 are connected to the inlet pipe 14 in the usual manner so that the connections may be individually relieved of their contents and the outlet pipe 4' leads to a 5 faucet 20 at a convenient place, such as a bar. It will thus be seen that as the 10 contents of the kegs are forced, by air or other approved means, through the inlet pipe of the container 1, said contents will be thoroughly cooled in the latter container and when extracted, at the faucet 20, will be in 15 fit condition for enjoyable drinking purposes.

From the foregoing description of the 20 construction of my improved device, the operation thereof will be readily understood and it will be seen that I have provided a device which will positively cool a liquid in a sanitary manner, as the same is drawn from the keg. It will still further be seen that I have provided a device which is simple and durable in construction, inexpensive to manufacture and one which will be very 25 efficient and useful in operation.

While I have particularly described the 30 elements best adapted to perform the functions set forth, it is obvious that various changes in form, proportion and in the minor details of construction may be resorted to without departing from the spirit or sacrificing any of the principles of the invention.

Having thus described this invention, what is claimed is:—

35 A cooling device of the class described comprising an outer transparent container having inlet and outlet ports formed in the

bottom thereof, a top for the container formed integral therewith and provided with an enlarged threaded opening, an inner transparent container externally threaded at its upper end for engagement with the threaded opening of the outer container to dispose said inner container within the latter, a laterally extending annular flange 40 formed on the upper peripheral edge of said inner container to contact with the upper face of the top of said outer container, whereby to limit the downward movement of the inner container in the outer container, 45 the wall of said inner container at the upper end thereof being increased in thickness from the inner face thereof, whereby to provide an opening of reduced diameter at the top of said inner container, a second inner container formed of foraminous material and disposed within the aforesaid inner container to fit snugly at its upper end against the wall of the reduced opening of said first mentioned inner container, the 50 upper peripheral edge of the second inner container being disposed slightly below the upper peripheral edge of the first mentioned inner container, a closure for said first mentioned inner container, and means for the admission of air to said outer container.

In testimony whereof I hereunto affix my signature in the presence of two witnesses.

JOSEPH MOSHER.
